PLURAL PENCIL WITH SLIDABLE LEAD CARRIERS

Walter Bossert, Pforzheim, Germany

Application March 23, 1949, Serial No. 82,950
In Switzerland March 27, 1948

11 Claims. (Cl. 120—14.3)

1

This invention relates to mechanical pencils in which a plurality of lead-carriers are selectively shifted from their position of rest to their position of work by slide-members moving in longitudinal slots of the casing, and is especially directed to pencils of the aforesaid type in which the backward movement of the lead-carriers to their position of rest is effected by means of helical springs.

It has already been known to the art to devise the actuating means of pencils of this kind in such a way that the forward shifting of one lead-carrier to its position of work automatically returns the previously used lead-carrier to its position of rest, whereby the operation of such pencils has been greatly facilitated.

However, known constructions of this type have the disadvantage that during the exchanging action a frictional contact between the lead-carriers can not reliably be prevented, which frequently results in the destruction of the pointed ends of the leads projecting from their appertaining carriers.

Another difficulty arises when the material used in making the casings is not sufficiently strong enough, as usually is the case in pencils made of precious metal. In pencils of this type the wall of the casing will bend inwardly, even under the strain of normal use, particularly at the places where the strength of the casing has been weakened by the longitudinal slots for the slide-members. And the aforesaid inward bending will then prevent the operating means, which have the shape of a long and slotted sleeve arranged in the interior of the casing, from performing the rotation which causes the release of the lead-carrier previously used from its position of work.

In order to overcome the disadvantages of the known device the present invention does no longer couple the retracting operation of one lead-carrier to the projecting movement of another lead-carrier.

According to the present invention the release of the means which lock the lead-carrier in its position of work is effected through slight backward shifting of a slide-member, whereupon the lead-carrier automatically returns to its position of rest, due to the action of its spring. And it is only after the lead-carrier has thus been retracted from its projected position, that the forward shifting of the next lead-carrier takes place.

The slide-members by means of which the backward shifting and the release of the lead-carrier is effected consist of one or a plurality of

2

slide-heads or of a shifting ring surrounding the casing on the outside. But it is also possible to devise the slide-heads, which move the lead-carriers to their position of work, in such a way, that slight backward shifting of a slide-head, whose appertaining lead-carrier is in its position of rest, will cause the release of the locking means of a lead-carrier which is in its position of work.

The characteristic features of the present invention are: a plurality of lead-carriers equipped with a return spring and a rearwardly extending guiding-shaft provided with an inwardly extending resilient end portion; a support on which the inwardly extending resilient end portion lodges itself when its appertaining lead-carrier has reached its position of work and thereby supports its lead-carrier in that position of work; a spring-pressed release member positioned before said support; and slide-members arranged in slots of the casing and adapted to displace through backward shifting in their slot said release-member against the pressure of its spring toward said support to thereby dislodge the resilient end of the guiding-shaft from its support, for the purpose of returning its appertaining lead-carrier to its position of rest.

The invention will be best understood from a consideration of the following detailed description taken in connection with the accompanying drawings, forming a part of this specification, with the understanding however, that the invention is not confined to any strict conformity with the showing of the drawings but may be changed or modified so long as such changes or modifications mark no material departure from the salient features of the invention as expressed in the appended claims.

In the drawings in which similar reference characters indicate like parts in the different figures:

Fig. 1 is a longitudinal sectional view of the first form of construction.

Figs. 2 and 3 are longitudinal sectional views of the rear portion of the pencil showing the locking and operating means on an enlarged scale.

Fig. 4 represents two cross-sections on line 4—4 of Fig. 2.

Figures 5 and 5a represent a fragmentary longitudinal sectional view of the inner casing and a cross-section on line 5a—5a of the latter.

Figures 6 and 6a represent an elevational view and a bottom plan view of a cross-like member forming the guide-ways for the lead-carrier shafts.

Figures 7 and 7a represent a front and a side elevation of a lead-carrier shaft.

Figures 8 and 8a represent a fragmentary elevational view and a central longitudinal sectional view of a slide-bar provided with a slide-head.

Figures 9 and 10 are front and side views and Fig. 9a a longitudinal sectional view of slide-head portions.

Figs. 11 and 12 are fragmentary longitudinal sectional views on an enlarged scale of the locking and operating means of the second and third form of construction. Fig. 11 is a section on line 11-11 of Fig. 13.

Figs. 13 and 14 are cross-sections on line 13-13 of Fig. 11 and on line XIV-XIV of Fig. 12.

Figures 15 and 15a represent a fragmentary longitudinal sectional view and a cross-section of the inner casing of the second form of construction.

Figures 16 and 16a represent a side and a bottom, end elevational view of the cross-like member forming the guide-ways for the lead-carrier shafts of the second form of construction.

Figures 17 and 17a represent front and side elevations of a lead-carrier shaft and Figs. 18 and 18a side elevational and longitudinal sectional views of the rear portion of a slide-bar of the third form of construction.

Referring now to the drawings in detail, the pencil is provided, in all of the several forms of construction illustrated in the different figures, with an outer casing 1 and with an inner casing 2, positioned in said outer casing. The inner casing terminates at its forward end in a front-wall 3, which forms one of the abutments of the helical springs or return springs 4 of the lead-carriers 5. The front-wall 3 is provided with the guide-passages 6 through which the lead-carriers 5 are shifted and guided from their position of rest to their position of work and vice versa. (Fig. 1). At their rear ends the lead-carriers are equipped with the annular shoulders 7, which serve as abutments for the rear ends of the springs 4 and to which are secured the flat shafts 9 provided with a short longitudinal slot 8. At its rear end the inner casing 2 is closed up by a closure-member 10 of cross-like conformation, which is so designed that it also serves as a means for guiding the shifting movement of the shafts 9, which extend through the guide-passages in the member 10 defined by angular grooves in the arms 11 into the rear portion of the pencil. Mounted on the member 10 and made integral therewith is a bolt 12, which is threaded at its end and onto which a sleeve 13 has been screwed, which is so devised that it may be serve as a magazine for spare leads. Arranged on bolt 12 between cross 10 and the forward end of sleeve 13, is a cup-shaped release member 14 in such a way that the central portion of bolt 12 forms the guide-bar for the release member. The release member 14 is provided with a helical spring 15 interposed between the front end 30 of sleeve 13 and a central recess in the top of the release member with the result that the latter is resiliently pressed against the rear end of cross 10 (Figs. 2 and 11). Provided at the outer circumference of the rear portion of sleeve 13 and preferably made rigid therewith is an annular shoulder 16, into which through the casing 1 a screw 17 has been screwed. It will be noticed that by arranging all of the lead-carriers 5 as an associated group or bundle by means of the inner casing 2 in the manner described, it will be easy to introduce the lead-

carriers into, and to withdraw them out of, the outer casing 1. In other words, the parts 10, 12, 13 and 16 are secured to the inner casing 2 and hence after the screw member 17 has been released or unscrewed and subsequently to the removal of the knobs 26, 23, the entire mechanical equipment of the pencil can be withdrawn rearwardly.

The inner casing 2 is provided with the longitudinal slots 18, and in addition to that, on its outside, with the guide-tracks 19 for the slide-bars 20. The guide-tracks 19 are concealed from view by the outer casing 1 (Figs. 4, 13 and 14). Mounted on the slide-bars 20 is a slide-head, by means of which the lead-carrier 5 is shifted into its position of work. The slide-head consists of a member 21 rigidly secured to the slide-bar 20 and extending through the guide-slots 22 of casing 1 to the outside of the casing 1. Mounted on the outer end of member 21, on both sides of the slot 22, are two side-members 23 which slightly project above the member 21 and which are fastened to the latter by means of a rivet 24. Inserted into the space 25 between the two projecting side-members 23, hereinafter called head 23, is an angular member 26, riveted to the head 23 as at 27. (Figs. 9 and 10.) The angular member 26 is the important part of the head 23, and together with the latter slides in the slots 22. The member 26 is provided, at one of its ends, with the actuating arm 28, which extends through a perforation 29 in the slide-bar 20 and through the longitudinal slot 18 of the inner casing 2 into the interior of the pencil and engages in the short longitudinal slot 8 of shaft 9 of the lead-carrier.

The features of the invention hereinbefore disclosed are those which are alike to all of the several forms of construction described in the present invention. Hereafter those features will be described in which the several forms of construction differ from one another.

In the first form of construction the actuating arm 28 is so dimensioned that it extends into the interior of the casing 2 beyond the lateral edges of the release member 14 (Fig. 2) and takes up its position before the forward edge of the latter, due to the pressure of the return spring 4, which just suffices to return the slide-head 23 to the aforesaid position, but which is not strong enough to overcome the counter-pressure exerted against the release member 14 by the helical spring 15. In the first form of construction the short longitudinal slot 8 of the shafts 9 is of such length that the actuating arm 28 engaging in it may perform in it a small additional backward movement A, notwithstanding the fact, that the lead-carriers in their position of rest almost or actually abut the forward edge of cross 10, and that, for that reason, it is impossible for their appertaining shafts 9 to move still farther to the rear. If the aforesaid backward movement of head 23 takes place when the associated lead-carrier is in its position of rest, the backward movement will cause the displacement of the release member 14 from the position illustrated in Fig. 2 to the position shown in Fig. 3. In the latter position the member 14 has forced its way behind the resilient rear end of shaft 9 whose appertaining lead-carrier is at that moment in its position of work, and by so doing has dislodged the rear end of that shaft from its supporting place on the forward end 30 of sleeve 13, where, owing to its resiliency, the rear end had lodged itself during the fore-

ward movement of its lead-carrier. After the rear end has thus lost its foothold, its lead-carrier 5 returns to its position of rest, due to the action of its return-spring 4. The loose engagement of the actuating arm 28 in slot 8 of the shaft 9 suffices to shift a lead-carrier 5 from its position of rest to its position of work, provided that, prior to the shifting, the lead-carrier previously used had been returned to its position of rest through slight backward shifting of a slide-head 23 appertaining to a lead-carrier which at that moment was in its position of rest.

In the second and third form of construction the slide-heads 23 are exclusively used for shifting the lead-carriers from their position of rest to their position of work. For releasing the lead-carriers from that position of work these modifications provide special releasing means. In the construction illustrated in Figs. 11 and 13 the releasing is done by means of two slide-heads 31 diametrically arranged with respect to each other and at an angle of 45° with respect to the slide-heads 23, while in the modification of Figs. 12 and 14 the releasing is effected with the aid of a shifting ring 32 surrounding the casing on its outside.

Each slide-head 31 (Fig. 13) is provided with an actuating arm 33 which extends through special slots 34 and 35 in the outer casing 1 and the inner casing 2 and bears against the forward edge of the release member 14 (Fig. 11). In a position of rest the arm 33 engages in a small recess 36 of the cross 10, in which it is locked by the pressure exerted by the spring 15 upon the release member 14. But slight backward shifting of the slide-head 31 will displace the release member toward the rear and thereby accomplish the same result as the backward shifting of the slide-heads 23 of the first form of construction.

The same applies to the operation of the shifting ring 32 of the third form of construction. Here, too, backward shifting of the ring will dislodge shaft 9 from its position on the forward edge of sleeve 13 and return the appertaining lead-carrier to its position of rest. In this construction the arms 36 projecting inwardly from the ring 32 extend through two longitudinal slots 22 of the outer casing 1, in which also the slide-heads 23 move, but which, for that purpose, have been somewhat lengthened toward the rear. They further extend through long slots 37 in two slide-bars 20 and slots 38 in two lead-carrier shafts 9 and abut against the forward edge of the release member 14 (Fig. 12). The length of the slots 37 and 38 corresponds to the length of the shifting path of the lead-carriers 5 from their position of rest to their position of work and vice versa. Fig. 12 shows the shifting-ring in releasing position. Manifestly, variations may be resorted to and parts and figures may be modified or used without others within the scope of the appended claims.

What I claim as new and desire to secure by Letters Patent of the United States is:

1. In a pencil of the type described, a casing provided with a plurality of longitudinal slots; a plurality of lead-carriers suitably positioned within said casing and adapted to be shifted from their position of rest to their position of work; locking means for each of said lead-carriers adapted to lock the lead-carrier in its position of work; releasing means suitably arranged with respect to said locking means and adapted to release said locking means from its locking position; a helical spring for each of said lead-

carriers adapted to retain its lead-carrier in its position of rest and to return its lead-carrier from its position of work to its position of rest after release of said locking means; and actuating means slidably mounted in each of said longitudinal slots and adapted to shift said lead-carriers to their position of work through forward shifting in said longitudinal slots, and to cause said releasing means to release said locking means and thereby return a lead-carrier from its position of work to its position of rest through backward shifting in said longitudinal slots prior to shifting another lead-carrier to its position of work.

2. In a pencil of the type described, an outer casing; a plurality of lead-carriers suitably positioned within said casing and adapted to be moved from their position of rest to their position of work and vice versa; a longitudinal slot provided in said casing for each of said lead-carriers; a supporting member rigidly arranged in the rear portion of the pencil; a guiding-shaft for each of said lead-carriers attached with its forward end to the end of its lead-carrier and extending with its rear end toward the rear end of the pencil and having a free resilient end portion inwardly turned toward the axis of the pencil, said free resilient inwardly turned end portion being adapted to be lodged against said supporting member when its appertaining lead-carrier is moved into working position, to thereby retain its lead-carrier in its working position; a release member resiliently mounted before said supporting member and adapted to be shifted toward said supporting member and to displace said resilient end portion of said guiding-shaft from its supporting position against said supporting member; a helical spring mounted on each of said lead-carriers and adapted to retain its lead-carrier in its position of rest and to return its lead-carrier from its position of work to its position of rest after displacement of said resilient end portion from said supporting member; and actuating means consisting of a slide-member for each of said lead-carriers, slidably mounted in said longitudinal slots and adapted to transfer its appertaining lead-carrier from its position of rest to its position of work through forward shifting toward the front end of the pencil, and to cause said release member to displace said resilient end portion of said guiding-shaft from its supporting position on said supporting member and thereby return a lead-carrier from its position of work to its position of rest through backward shifting toward the rear end of the pencil, prior to the forward shifting of another lead-carrier to its position of work.

3. A plural mechanical pencil according to claim 2, wherein the release of a lead-carrier from its position of work is effected by the backward shifting of a slide-member appertaining to a lead-carrier which is in its position of rest.

4. A plural mechanical pencil according to claim 2, wherein the release member is provided with a helical spring, and in which said backward shifting of said slide-member forces said release member against the pressure of its spring toward said supporting member and behind the end portion of said guiding-shaft lodged on said supporting member, for the purpose of displacing said end portion of said guiding shaft from its supporting position on said supporting member, to thereby release the lead-carrier supported by said guiding-shaft from its position of work.

5. A plural mechanical pencil according to

claim 2, in which each of said guiding-shafts is provided with a slot, and in which each of said slide-members is mounted on a slide bar slidably arranged beneath said longitudinal slots of said casing and above its respective lead carrier and guiding shaft, and in which each of said slide-members is provided with an actuating arm extending into the respective slot of each of said guiding-shafts for the purpose of shifting said guiding shaft and its appertaining lead-carrier into working position.

6. A plural mechanical pencil according to claim 2, in which each of said guiding-shafts is provided with a slot, and in which each of said slide-members are provided with an actuating arm extending through said longitudinal slot in said casing and through the respective slot in each of said guiding shafts into the interior of said casing before the front edge of said release-member, for the purpose of displacing said release member toward said supporting member through backward shifting of said slide-member in said longitudinal slot.

7. A plural mechanical pencil according to claim 2, in which each of said guiding shafts is provided with a longitudinal slot, and in which each of said slide-members is provided with an actuating arm extending through said longitudinal slot in said casing and in said guiding-shaft into the interior of said casing before the front edge of said release member, and in which said longitudinal slots in said casing and in said guiding-shafts are of such length and so positioned that slight backward shifting of a slide-member appertaining to a lead-carrier which is in its position of rest will displace said release member toward said supporting member sufficiently to cause the release of said locking means.

8. A plural mechanical pencil according to claim 2, in which said pencil includes a removable inner casing in which said plurality of lead-carriers are arranged, said inner casing comprising an outer cylindrical wall provided with a plurality of longitudinal slots corresponding in number to the number of slots in said outer casing, a front-wall provided with a guide-passage for the front-portions of each of said lead-carriers, and a removable rear-wall provided with a guide-passage for each of said guiding-shafts of said lead-carriers.

9. In a mechanical pencil of the type described, an outer casing; a plurality of lead-carriers suitably positioned within said casing and adapted to be moved from their position of rest to their position of work and vice versa; a longitudinal slot provided in said casing for each of said lead-carriers; a supporting member rigidly arranged in the rear portion of the pencil; a guiding-shaft for each of said lead-carriers attached with its forward end to the end of its lead-carrier and extending with its rear end toward the rear end of the pencil and having a free resilient end portion inwardly turned toward the axis of the pencil, said free resilient inwardly turned end portion being adapted to be lodged against said supporting member when its appertaining lead-carrier is moved into working position, to thereby retain its lead-carrier in its working position; a release member resiliently mounted before said supporting member and adapted to be shifted toward said supporting member and to displace said resilient end portion of said guiding-shaft from its supporting position on said supporting member; a helical spring mounted against each of said lead-carriers and adapted to retain its lead-carrier in

its position of rest and to return its lead-carrier from its position of work to its position of rest after displacement of said resilient end portion from said supporting member; actuating means consisting of a slide-member for each of said lead-carriers adapted to transfer its appertaining lead-carrier from its position of rest to its position of work through forward shifting towards the front end of the pencil, said slide members being mounted on slide-bars slidably arranged beneath said longitudinal slots of said casing and above said guiding-shafts of said lead-carriers, said slide-bars and said guiding-shafts formed with long slots and said longitudinal slots in said casing being formed with extensions towards the rear end of said casing, and a plurality of special slide-members for actuating said release member mounted in said extensions of said longitudinal slots and provided with actuating arms designed to extend through said extensions of said slots in said casing and said long slots in said slide-bars and said guiding-shafts into the interior of said casing before the front edge of said release member and to move said release member into releasing position through backward shifting of said special slide-members.

10. In a mechanical pencil of the type described, an outer casing; a plurality of lead-carriers suitably positioned within said casing and adapted to be moved from their position of rest to their position of work and vice versa; a longitudinal slot provided in said casing for each of said lead-carriers; a supporting member rigidly arranged in the rear portion of the pencil; a guiding-shaft for each of said lead-carriers attached with its forward end to the end of its lead-carrier and extending with its rear end toward the rear end of the pencil and having a free resilient end portion inwardly turned toward the axis of the pencil, said free resilient inwardly turned end portion being adapted to be lodged against said supporting member when its appertaining lead-carrier is moved into working position, to thereby retain its lead-carrier in its working position; a release member resiliently mounted before said supporting member and adapted to be shifted toward said supporting member and to displace said resilient end portion of said guiding-shaft from its supporting position on said supporting member; a helical spring mounted against each of said lead-carriers and adapted to retain its lead-carrier in its position of rest and to return its lead-carrier from its position of work to its position of rest after displacement of said resilient end portion from said supporting member; actuating means consisting of a slide-member for each of said lead-carriers adapted to transfer its appertaining lead-carrier from its position of rest to its position of work through forward shifting towards the front end of the pencil, said slide members being mounted on slide-bars slidably arranged beneath said longitudinal slots of said casing and above said guiding-shafts of said lead-carriers, said slide-bars and said guiding-shafts formed with long slots and said longitudinal slots in said casing being formed with extensions towards the rear end of said casing, and a shifting ring for the actuation of said release member surrounding the pencil on its outside behind said slide-members and provided on its inside with a plurality of actuating arms designed to extend through said extensions of said slots in said casing and said long slots in said slide-bars and said guiding-shafts into the interior of said casing be-

fore the front edge of said release member and to move said release member into releasing position through backward shifting of said special slide-members.

11. In a mechanical pencil of the type described, an outer casing; a plurality of lead-carriers suitably positioned within said casing and adapted to be moved from their position of rest to their position of work and vice versa; a longitudinal slot provided in said casing for each of said lead-carriers; a supporting member rigidly arranged in the rear portion of the pencil; a guiding-shaft for each of said lead-carriers attached with its forward end to the end of its lead-carrier and extending with its rear end toward the rear end of the pencil and having a free resilient end portion inwardly turned toward the axis of the pencil, said free resilient inwardly turned end portion being adapted to be lodged against said supporting member when its appertaining lead-carrier is moved into working position, to thereby retain its lead-carrier in its working position; a release member resiliently mounted before said supporting member and adapted to be shifted toward said supporting member and to displace said resilient end portion of said guiding-shaft from its supporting position on said supporting member; a helical spring mounted against each of said lead-carriers and adapted to retain its lead-carrier in its position of rest and to return its lead-carrier from its position of work to its position of rest
